[57] CLAIM

The ornamental design for a shelf, as shown and described.

DESCRIPTION

FIG. 1 is a bottom perspective view of a shelf showing my new design;

FIG. 2 is a front elevational view thereof;

FIG. 3 is a rear elevational view thereof;

FIG. 4 is a top view thereof;

FIG. 5 is a bottom view thereof; and,

FIG. 6 is a right side elevational view, the undisclosed left side being a mirror image.

The broken lines shown in the drawings are for illustrative purposes only and form no part of the claimed design.
